(57) **CLAIM**

The ornamental design for a plastic cup, as shown and described.

DESCRIPTION

FIG. 1 is a top perspective view of a plastic cup, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately inside the handle in FIG. 3 represent the bounds of the claimed design and form no part of the claimed design, while all other broken lines illustrate portions of the plastic cup that form no part of the claimed design.
